UNITED STATES PATENT OFFICE.

HUMPHREYS W. JORDAN, OF PELZER, SOUTH CAROLINA, ASSIGNOR TO DRAPER COMPANY, OF HOPEDALE, MASSACHUSETTS, A CORPORATION OF MAINE.

CLAMPING DEVICE FOR HEDDLE BARS OR SUPPORTS.

SPECIFICATION forming part of Letters Patent No. 742,120, dated October 20, 1903.

Application filed July 20, 1903. Serial No. 166,227. (No model.)

To all whom it may concern:

Be it known that I, HUMPHREYS W. JORDAN, a citizen of the United States, and a resident of Pelzer, county of Anderson, State of South Carolina, have invented an Improvement in Clamping Devices for Heddle Bars or Supports, of which the following description, in connection with the accompanying drawings, is a specification, like characters on the drawings representing like parts.

This invention has for its object the production of a novel, simple, and efficient device for locking or clamping in place the detachable harness or heddle support in a harness-frame, particularly of the type wherein the heddles serve also as warp-stop-motion-controlling detectors.

By the means forming the subject-matter herein the heddle-support is positively and firmly held in position, while its ready removal when desired is also made possible.

Figure 1 is a front elevation, centrally broken out, of a harness-frame embodying one form of my invention, the side bars also being broken out and one of the heads being shown partly in section. Fig. 2 is a side elevation of one of the heads with the locking device for the heddle-support in position. Fig. 3 is a similar view, but from the opposite side of the head, showing the longitudinal slot therein. Fig. 4 is a perspective view, enlarged and detached, of the follower; and Fig. 5 is an enlarged side elevation of the follower and the locking or clamping bolt.

Referring to Fig. 1, the bottom cross-bar a^x of the harness-frame has secured to it upright side bars a , shown as rods, which are preferably threaded at their upper ends to enter correspondingly-threaded bosses b' of heads b , the latter being conveniently made as castings. Each head has a longitudinal slot b^2 extended therethrough, reduced in width at its lower portion at b^3 and leaving shoulders 20, (see Fig. 3,) the walls of the portion b^3 being shown in said figure as slightly convergent toward the bottom of the seat. A transverse pin b^x crosses the seat for a purpose to be described. The heddle-support h , shown as a flat bar, is notched in its lower

edge near each end, as at h^x , Fig. 1, to embrace the pin b^x when the ends of the support are inserted in the seats b^3 to prevent any relative lateral movement of the side bars of the frame and the heddle-support when the latter is in position. The support is applied by inserting its ends in the wider ends b^2 of the slots, and then the heddle-support is pushed down into the seats, the notches h^x engaging the cross-pins b^x , the construction so far described being substantially as shown in United States Patent No. 729,047.

In order to hold the support h down in the seats during the shedding operation, I have provided a follower which is slidably mounted in the upper end of the slot of each head, the follower being shown separately in Figs. 4 and 5, and, referring thereto, the body f of the follower is shown as a flat plate corresponding in length to the width of one of the heads b and adapted to enter easily the part b^2 of the slot, the upper and lower edges of the body being longitudinally grooved, as at f^1 f^2 , respectively. At one end the body is provided with an enlarged ear f^3 in a plane at right angles to the body, this ear resting against, preferably, the outer side of the head, as shown clearly in Figs. 1 and 2. The shoulders 20 prevent the follower from dropping down or becoming wedged in the portion b^3 of the slot when the heddle-support is removed. The ear f^3 is provided with a hole f^x in alignment with the upper grooved edge of the body f , and a clamping or locking bolt c is extended through the slot of the head b and through the hole f^x in the ear of the follower, the bolt being supported in the groove f' of the latter, as shown in Fig. 5. The head c' of the bolt is nicked, as at c^2 , and between the bolt-head and the adjacent side of the head b of the frame a washer w is interposed, while a retaining-nut c^x is set up on the threaded end of the bolt projecting beyond the ear f^3 of the follower. When the support h is seated in the portions b^3 of the slots, the followers are brought down to rest upon the upper edge of said support, the grooves f^2 firmly engaging said upper edge, and then the nuts c^x are set up, thereby firmly clamp-

ing or locking the followers to the heads. The bolt-heads are nicked, so that a screw-driver may be employed to prevent turning of the bolt, if necessary, when setting up the nuts 5 c^x . When it is desired to remove the heddle-support, it is only necessary to slacken up the nut c^x , when the operative can slide the follower upward far enough to permit the removal of the support.

10 The construction is simple, strong, and provides a positive downhold and lock for the heddle-support.

Having fully described my invention, what I claim as new, and desire to secure by Letters 15 Patent, is—

1. In a loom harness-frame, side bars having heads each provided with a longitudinal slot, a detachable heddle-support adapted to be seated at its ends in the slotted heads, a 20 follower on each head and slidale in the slot thereof, to engage the edge of and hold the heddle-support in position, and a locking-bolt mounted on and to clamp the follower on the head.

25 2. In a loom harness-frame, side bars having heads each provided with a longitudinal slot widened at its upper end, a detachable heddle-support adapted to be seated at its ends in

the lower end of each slot, a follower movable in the widened end of the slot and adapted to 30 engage the upper edge of and position the heddle-support when seated, and a clamping-bolt carried by each follower and adapted to coöperate with the head and lock the follower from movement.

3. In a loom harness-frame, side bars having heads each provided with a longitudinal slot, a detachable heddle-support adapted to be seated at its ends in the bottoms of the slots, means to prevent lateral movement of 35 the heads when said support is in place, a follower slidale in each slot and having an external, transverse ear, and a clamping-bolt carried by the ear and extended through the slot to engage the opposite side of the head, 40 to lock the follower from movement when in engagement with the upper edge of the heddle-support.

In testimony whereof I have signed my name to this specification in the presence of 50 two subscribing witnesses.

HUMPIIREYS W. JORDAN.
